UNITED STATES PATENT OFFICE.

HENRY C. MILLER, OF MILWAUKEE, WISCONSIN.

BOOK-COVER HINGE.

Application filed September 3, 1921. Serial No. 498,503.

To all whom it may concern:

Be it known that I, HENRY C. MILLER, a citizen of the United States, and resident of Milwaukee, in the county of Milwaukee and State of Wisconsin, have invented certain new and useful Improvements in Book-Cover Hinges; and I do hereby declare that the following is a full, clear, and exact description thereof.

10 My invention pertains to improvements in book cover hinges and is directed more particularly to that type of book commonly known as a loose leaf binder.

At the present time two methods are commonly employed for hinged connecting book covers to the binder fixtures; namely:—

20 To rivet to the cover a metal hinge socket adapted to receive the pintle carried by the binder fixture, or to provide a flexible fabric or canvas connection between the cover and binder fixture. The former method while durable, is rather expensive, in that special dies are required to form the hinge 25 and skilled labor is required to secure or attach the same to the cover board. The latter method, although a very cheap construction, is not substantial and the cover soon becomes loose with respect to the 30 binder fixture. It is therefore primarily the object of the present invention to overcome these objections and provide a simple, inexpensive, and at the same time, durable hinge connection, which does not require 35 skilled labor to assemble and which can be attached to the cover by suitable adhesive. This operation may be performed by unskilled labor.

40 A further object, incidental to the foregoing, resides in the provision of a hinge of this character in which a rigid reinforcement adhered to the cover is employed to engage the pintle. A more specific object, is to provide a hinge constructed of stock material, thereby eliminating the expense of 45 dies and a special forming operation.

With the foregoing and other objects in view, my invention consists in what is herein shown and described, and more particularly pointed out and defined by the appended claims.

Several methods of carrying out the present invention are illustrated in the accompanying drawing, in which:—

55 Figure 1 is a plan view of the hinge as applied to the loose leaf binder with parts

broken away to more clearly illustrate the invention.

Figure 2 is a transverse sectional view taken on the line 2—2 of Figure 1. 60

Figure 3 is a view similar to Figure 2 showing a modified form of the invention.

Referring now more particularly to the drawing, the numeral 1 designates a binder fixture provided with the customary binding post 1' to which leaves are secured in the usual manner. The ends of the binding fixture are provided with laterally projecting lugs 2 in which are secured the ends of a pintle 4. It is obvious that while I 70 have only shown lugs provided at the ends of the binding fixture, in some instances I may desire to use central lugs in addition thereto.

Surrounding the pintle is a metallic sleeve 75 5 which as shown at Figure 2 is nested in the concaved edge of the cover board 6, the latter having its corners cut away as shown at 7 to permit the same to be received between the ends of the lugs 2. Attention is 80 directed to the fact, that while I have shown the edge of the cover board 6 as concave in order to form a seat for the sleeve 5, it is contemplated within the scope of the invention to make this edge straight in some instances. 85

As set forth in the foregoing objects, it has hitherto been customary to use an especially formed sleeve, and to secure the same to the cover board by riveting. In 90 carrying out my invention I provide a binding strip 8 of paper or textile fabric, which is folded around the sleeve 5 and adhered to the cover board, to hold the sleeve tightly in engagement with the edges thereof. This 95 operation may be performed by unskilled operators, either manually or on what is commonly known in this particular art as a gluing machine, at the same time that the binding 9 is secured to the cover board. 100 This binding may be of leather, buckram, or any suitable material commonly used for this purpose.

In the modified form of my invention as disclosed in Figure 3 of the drawing, I substitute for the sleeve 5 a metallic reinforcing strip 5', which I secure to the cover board 6 with any suitable adhesive. The plate 5' projects slightly past the edge of the cover board and in conjunction with the edge, 110 forms a pocket to receive the pintle 4. A binding strip 8' is folded over the edge of

the cover and adhered thereto. This serves to secure the cover on the pintle and also assists in holding the reinforcing strip 5'.

In both forms of my invention the reinforcing strip 5', or the sleeve 5, extend the entire length between the lugs 2 and abut the same, thereby preventing lateral movement of the cover on the pintle, and also serving as a brace between the lugs to prevent them from being bent inwardly.

From the foregoing it will be obvious, that a very simple structure has been obtained, which provides a durable and rigid hinge connection between the cover board 15 and binder post. Further, due to the fact that I employ stock material as a reinforcing element the hinge is inexpensive and cheap to manufacture.

I claim as my invention:—

1. In a device of the character described, a binder fixture having laterally projecting lugs, a pintle carried by the lugs, a cover board having a rigid reinforcement adjacent one of its edges, said reinforcement engaging the pintle, and a binding strip folded over the edge and adhered to the cover to secure the same to the reinforcement.

2. In a device of the character described,

a binder fixture having laterally projecting lugs, a pintle carried by the lugs, a sleeve 30 surrounding the pintle, a cover board having a strip of material folded over one edge and secured thereto to enclose the sleeve between said strip and the edge of the cover.

3. In a device of the character described, 35 a binder fixture having laterally projecting lugs, a pintle carried by the lugs, a cover board having a reduced edge portion adapted to be received between said lugs, a strip folded over said reduced edge portion and 40 adhered thereto, a sleeve enclosed between the strip and said edge and surrounding said pintle.

4. In a device of the character described, 45 a binder fixture having laterally projecting lugs, a pintle carried by said lugs, a sleeve surrounding the pintle, a cover board having a concave edge in which said sleeve is nested, a strip of material folded around the sleeve and adhered to the cover board 50 so as to secure said sleeve rigidly thereto.

In testimony that I claim the foregoing I have hereunto set my hand at Milwaukee, in the county of Milwaukee and State of Wisconsin.

HENRY C. MILLER.
